United States Patent Office

Des. 196,172
Patented Sept. 3, 1963

196,172

DOOR

Jack Carlow, 4309 Don Carlos Drive,
Los Angeles, Calif.

Filed May 28, 1962, Ser. No. 70,325

Term of patent 14 years

(Cl. D13—1)

FIG. 1 is a front elevation of a door showing my new design, the rear being substantially the same in appearance.

FIG. 2 is a side elevation of a door.

FIG. 3 is a typical section plan showing details of door frame and moulding.

I claim:

The ornamental design for a door, as shown and described.
